LOUIS M. FABBRO, OF CLEVELAND, OHIO, ASSIGNOR OF FORTY-FIVE PER CENT TO ANNA M. FABBRO, AND FORTY PER CENT TO E. C. BALZHISER, BOTH OF CLEVELAND, OHIO, AND FIFTEEN PER CENT TO CHARLES DI LORENZIO

VAPORIZER AND SUPERCHARGER FOR INTERNAL COMBUSTION ENGINES

Application filed September 19, 1930. Serial No. 483,102.

This invention relates to a vaporizer and supercharger for internal combustion engines, the general object of the invention being to provide means for thoroughly vaporizing the explosive mixture before introducing the same into the cylinders of the engine, thereby greatly increasing the efficiency of the engine, reducing the consumption of fuel and preventing overheating and carbonization of the engine.

The present invention is an improvement over that forming the subject matter of applications filed by me on October 11, 1929, Serial No. 399,029, and on May 21, 1930, Serial No. 454,390.

The specific object of the present invention is to improve and simplify the construction and operation of the device and to provide an auxiliary air supply which is controlled by an automatic valve.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is an elevation of the invention, showing the same attached to certain parts of an engine.

Figure 2 is a longitudinal sectional view through the device.

Figure 3 is a section on line 3-3 of Figure 1.

Figure 4 is a section on line 4-4 of Figure 3.

In these drawings, the numeral 1 indicates a cylinder, the bore of which is shown at 2, and said cylinder is formed with an annular chamber 3 which is separated from the bore by the walls 4. The cylinder is formed with

two sections which are bolted or otherwise connected together, as shown at 5, and the abutting ends of the walls 4 of the two sections overlap, as shown at 6, to provide a gas-tight joint when the two sections are placed together.

A chamber 7 is formed at one end of the bore and an outlet port 8 is in communication with the other end, this port being connected with the inlet manifold 9 of the engine. A port 10 places the chamber 7 in communication with a carburetor 11 or other source of fuel supply and a passage 12 connects the chamber 7 with the atmosphere. This passage is normally closed by a valve 13, the spring 14 of which is adjustable by means of a nut 15 on the stem of the valve. A conduit 16 connects one end of the chamber 3 with the exhaust manifold of the engine and an outlet port 17 connects the other end of the chamber with a pipe 18 which is connected with the exhaust pipe of the engine.

A valve 19 controls the flow of exhaust gases through the conduit 16 and a gear 20 is fastened to the stem of the valve and is located in a housing 21 in which is also placed a gear 22 which meshes with the gear 20 and which is engaged by a segmental rack 23 carried by a thermostatic member 24 so that the movement of the member will be communicated to the valve. The thermostatic member is carried by a tube 25 which extends into an enlarged part of the chamber 3 so that the thermostatic member is acted on by the exhaust gases passing through the chamber 3. The tube 25 is held in place by a conical nut 26 threaded in a part of the casing and having its upper part split and of conical shape so that when the nut 27 is tightened on the split part, said part will be caused to grip the tube. A finger 28 is connected with the gear 22 and cooperates with a dial member 29 in the housing to indicate the temperature of the exhaust gas chamber of the device. The fin-

ger and dial member are visible through a window 30 in the housing.

A shaft 31 passes through the bore of the cylinder and has its ends journaled in the brackets 32 connected with the ends of the cylinder and this shaft is rotated from a movable part of the engine through means of a belt 33 or any other suitable means. Fan blades 34 are connected with the shaft and a spiral or helical 35 of foraminous material is connected with the shaft. Any suitable number of baffles 36 are also connected with the shaft and are formed of foraminous material and are located between the convolutions of the spiral. I prefer to place the fan adjacent the chamber 7 and to extend the spiral from said fan to the outlet end of the bore, as shown, though I do not wish to be limited to this specific arrangement of these parts.

From the foregoing it will be seen that the explosive mixture first enters the chamber 7 and then passes through the bore to the port 8 through which it passes into the inlet manifold and during its passage through the bore, the mixture is acted on by the fan, the spiral and the baffles which are all rotating in the bore. The mixture is also heated by the products of combustion passing through the chamber 3. Thus the mixture will enter the cylinders of the engine in a highly combustible state and air is automatically added to the mixture when the engine picks up speed through the valve controlled air port 12. The thermostatic means automatically control the temperature of the mixture, for when the thermostatic means come into action, the valve 19 is closed, which prevents the exhaust gases from entering the chamber 3 of the device.

While the drawings show the thermostatic device located in the chamber 3, I do not wish to be limited to this arrangement, as it might be desirable to extend the device into the bore 2, so that the thermostatic device will be acted on by the explosive mixture itself.

Thus I have provided means for thoroughly vaporizing and co-mingling the explosive mixture before the same enters the cylinders of the engine, the mixture being heated by the exhaust gases from the engine and the temperature to which the mixture is heated being automatically controlled by the thermostatic device.

This invention will produce a highly combustible mixture which will enable the engine to start quickly. The miles per gallon is greatly increased, and overheating and carbonization of the engine is prevented.

It is thought from the foregoing description that the advantages and novel features of the invention will be readily apparent.

It is to be understood that changes may be made in the construction and in the combination and arrangement of the several parts,

provided that such changes fall within the scope of the appended claims.

What I claim is:

1. A mixing device for an explosive mixture comprising a casing, means for introducing an explosive mixture into one end of the bore of the casing, means for discharging the mixture from the other end of the bore, a chamber surrounding the bore, means for passing a heating medium through the chamber to heat the mixture passing through the bore, a shaft passing through the bore, means for rotating the shaft, a fan carried by the shaft, a helical member carried by the shaft, means for connecting the bore to the atmosphere and an automatic valve controlling such connection. 75

2. A mixing device for an explosive mixture comprising a casing, means for introducing an explosive mixture into one end of the bore of the casing, means for discharging the mixture from the other end of the bore, a chamber surrounding the bore, means for passing a heating medium through the chamber to heat the mixture passing through the bore, a shaft passing through the bore, means for rotating the shaft, a fan carried by the shaft, a helical member carried by the shaft and formed of foraminous material, means for connecting the bore to the atmosphere, an automatic valve controlling such connection and a baffle member of foraminous material carried by the shaft and arranged between a pair of the convolutions of the helical member. 80 90

3. A mixing device for an explosive mixture comprising a casing, means for introducing an explosive mixture into one end of the bore of the casing, means for discharging the mixture from the other end of the bore, a chamber surrounding the bore, means for passing exhaust gases through the chamber to heat the mixture passing through the bore, thermostatic means for controlling the flow of exhaust gases through the chamber to automatically regulate the temperature of the explosive mixture, a shaft passing through the bore, means for rotating the same, a fan carried by the shaft, a helical member carried by the shaft and formed of foraminous material and baffle members of foraminous material carried by the shaft. 105 110 115

4. A mixing device for an explosive mixture, comprising a casing having a bore and a chamber surrounding the bore, said casing being formed of two sections, means for connecting the sections together, the wall portions separating the chamber from the bore overlapping at their abutting ends, a chamber formed at one end of the bore, means for discharging a mixture from the other end of the bore, a port connecting the second named chamber with the atmosphere, an automatic valve controlling said port, a shaft passing through the bore, fan blades on the shaft ad- 120 125 130

6 jacent the chamber, a helical member of
foraminous material carried by the shaft and
extending from the fan to the discharge end
of the bore, means for rotating the shaft,
means for introducing exhaust gases into the
5 first named chamber which surrounds the
bore and thermostatic means for controlling
the flow of gases into the chamber to auto-
matically regulate the temperature of the
mixture passing from the device.

10 In testimony whereof I affix my signature.
LOUIS M. FABBRO.
